J. F. MURPHY—

By N. S. Steele

Attorney

UNITED STATES PATENT OFFICE.

JAMES F. MURPHY, OF BROOKLYN, NEW YORK.

ASH SIFTER AND SCOOP.

1,234,195.

Specification of Letters Patent. Patented July 24, 1917.

Application filed February 9, 1917. Serial No. 147,655.

To all whom it may concern:

Be it known that I, JAMES F. MURPHY, a citizen of the United States, residing at Brooklyn, in the county of Kings, State of New York, have invented a new and useful Ash Sifter and Scoop; and I do hereby declare the following to be a full, clear, and exact description of the invention, such as will enable others skilled in the art to which it appertains to make and use the same.

The present invention relates to a combination ash scoop and sifter, and has for its object to provide a device of this character which embodies novel features of construction whereby the ashes can be easily sifted in the ash pit of a stove or furnace and the unburned particles of coal segregated and thrown back into the fire box, thereby resulting in great economy in the use of fuel.

Further objects of the invention are to provide a device of this character which is comparatively simple and inexpensive in its construction, which can be easily manipulated, which will successfully withstand the rough usage to which such devices are invariably subjected, and which will enable the ashes to be sifted without the usual annoying and disagreeable features.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:—

Figure 1 is a top plan view of an ash scoop and sifter constructed in accordance with the invention.

Fig. 2 is a longitudinal sectional view on the line 2—2 of Fig. 1, the swinging plate at the end of the scoop being shown as swung upwardly into a closed position.

Fig. 3 is a similar view with the swinging plate at the end of the scoop swung downwardly into an open position.

Fig. 4 is a top plan view of a slightly modified form of the invention.

Fig. 5 is a longitudinal sectional view through the modification shown by Fig. 4.

Corresponding and like parts are referred to in the following description and indicated in all the views of the drawings by the same reference characters.

Specifically describing the embodiment of the invention shown by Figs. 1 to 3 of the drawing, the reference character A designates a scoop which is open at the forward end in the usual manner, and has the bottom, back and sides thereof formed of wire meshing. A channel shaped sheet metal binding strip 1 may be applied to the forward edge of the bottom of the scoop for the purpose of reinforcing and protecting the same. A U-shaped reinforcing wire 2 is applied to the scoop with the sides or arms thereof extending along the upper edges of the sides 2^a thereof, the free ends 60 thereof being extended inwardly at 2^b at the back of the scoop and then extended outwardly from the middle of the back and twisted to provide a stem 2^c upon which the handle 2 is fitted, the extremities of the 65 wire being shown as coiled at the end of the handle, as indicated at 4, to hold the handle in position upon the stem, and also to provide an eye for hanging the device upon a nail or the like. At the forward end of 70 the scoop the side pieces 2^a of the U-shaped wire are bent downwardly at 2^d to bring the cross bar 2^e into the plane of the bottom of the scoop. A binding strip 5 of sheet metal 75 is shown as applied to the free edges of the 80 sides and back of the scoop, said binding strip serving both as a reinforcing means and also as a means for holding the edges of the wire meshing in engagement with the reinforcing wire 2. The cross bar 2^e of the 85 U-shaped reinforcing wire provides a pivot member upon which a swinging plate 6 is mounted, said swinging plate being adapted 90 either to be swung downwardly into substantial alinement with the bottom of the 95 scoop, as indicated by Fig. 3, or to be swung upwardly into an upright and closed position, as indicated by Fig. 2. The swinging plate is connected by a link 7 to a ring 8 which is slidable upon the handle 3, so that 100 by moving the ring back and forth upon the handle the plate can either be swung downwardly into an open position or upwardly into a closed position. In the present instance the end of the link 7 is shown 105 as engaging an eye 8^b upon the plate. The opposite ends of the plate 6 are rolled outwardly to provide sleeves 9 within which arms 10 are fitted, said arms projecting downwardly below the bottom of the scoop 110 when the swinging plate is in an upright position and thereby preventing ashes from

being dragged from the ash pit when the device is removed therefrom, and also serving as stops to engage the bottom of the scoop and limit the downward swinging movement of the plate.

The ring 8 is manipulated to swing the plate 6 downwardly, as indicated by Fig. 3, when inserting the device in the ash pit of a stove or furnace. After a quantity of 10 ashes have been scooped up the plate 6 is swung upwardly into a closed position, as indicated by Fig. 5, after which the device is given a back and forth reciprocating movement sufficient to agitate the ashes and 15 cause the fine particles to drop through the wire meshing. This is accomplished directly in the ash pit of the stove or furnace, and when the scoop is withdrawn the unburned particles of coal will be retained 20 therein.

A slight modification is shown by Figs. 4 and 5, in which a sheet metal scoop B has a large opening 11 cut in the bottom thereof and a piece of wire meshing 12 fitted over the said opening 11, said wire meshing being carried by a frame 13 which is secured by fastening members, such as the rivets 14, to the body of the scoop. As in the previous 25 instance a substantially U-shaped reinforcing wire 2 extends along the upper edges of the sides of the scoop, the free ends of the wire being extended inwardly at the back of the scoop and secured to a sleeve 15 within which the end of the handle 16 is fitted. 30 The cross bar of the U-shaped wire reinforcement is arranged adjacent the forward edge of the scoop bottom, as in the previous instance, and the swinging plate 6 pivotally 35

mounted thereon. The construction of this swinging plate 6 is exactly as previously described, said plate being connected by a long link or arm 7^a to a ring 8^a which is slideable upon the handle 16. The longer handle 16 enables this form of the invention to be used to a little greater advantage in connection 40 with furnaces, although the manner of operation and all of the essential features of construction are the same as has been previously described.

Having thus described the invention, what 50 I claim as new and desire to secure by Letters Patent, is:—

A combination ash scoop and sifter including a scoop member provided with sides and a back and having an open front, a 55 handle for the scoop, a cross bar extending across the scoop adjacent the forward edge of the bottom, a swinging plate pivoted upon the said cross bar and adapted either to be swung downwardly into alignment 60 with the bottom of the scoop or upwardly into an upright position, the ends of the plate being provided with sleeves, arms fitted within the sleeves and projecting downwardly for engagement with the bottom of 65 the scoop to limit the downward swinging movement of the plate, and means upon the handle for manipulating the plate.

In testimony whereof I have signed my 70 name to this specification in the presence of two subscribing witnesses.

JAMES F. MURPHY.

Witnesses:

THOMAS HARTNETT,
PETER NIELSEN.
